MERCHANDISE DISPLAY RACK

Joe Zel, Cleveland Heights, and Robert W. Latimer, Bay Village, Ohio, assignors to American Greetings Corporation, a corporation of Ohio

Application May 8, 1951, Serial No. 15,094

Term of patent 14 years

(Cl. D80—10)

To all whom it may concern:

Be it known that we, Joe Zel and Robert W. Latimer, citizens of the United States and residents respectively of Cleveland Heights, in the county of Cuyahoga and State of Ohio, and Bay Village, in the county of Cuyahoga and State of Ohio, have invented a new, original, and ornamental Design for a Merchandise Display Rack, of which the following is a specification, reference being had to the accompanying drawings forming a part hereof.

In said drawings,

Fig. 1 is a front perspective view of a merchandise display rack showing our new design; and

Fig. 2 is a side elevational view thereof.

We claim:

The ornamental design for a merchandise display rack, as shown.

JOE ZEL.

ROBERT W. LATIMER.
